UNITED STATES PATENT OFFICE.

ORVILLE MARSHALL KNOX OF KNOXBORO, NEW YORK.

RAILWAY CROSS-TIE.

1,274,897.

Specification of Letters Patent.

Patented Aug. 6, 1918.

Application filed January 29, 1918. Serial No. 214,350.

To all whom it may concern:

Be it known that I, ORVILLE M. KNOX, a citizen of the United States, residing at Knoboro, in the county of Oneida and State 5 of New York, have invented new and useful Improvements in Railway Cross-Ties, of which the following is a specification.

This invention relates to the class of railway cross-ties which are formed of metal, 10 and particularly to improvements in the type of tie shown in my prior Letters Patent No. 685,213, dated October 22, 1901.

In my aforesaid patent I have shown a tie composed of a top plate having down- 15 turned vertical end portions forming anchoring members, said plate having a medial longitudinally extending web depending centrally therefrom on the underside thereof between said downturned ends of the 20 plate, thus forming a tie which is T-shape in cross section and provided with transverse end anchoring portions and a longitudinally extending central anchoring portion.

The primary object of the present invention 25 is to provide improved auxiliary means for strengthening and reinforcing the top plate on opposite sides of the longitudinally extending anchoring web, and for also reinforcing the downturned end portions and at 30 the same time providing additional means at the sides of the tie for more firmly and securely anchoring the same in the ballast.

A further object of the invention is to 35 provide supplementary reinforcing and anchoring portions consisting of longitudinally extending strips secured to the underside of the top plate adjacent to the side edges thereof, and from end to end of said top plate 40 between the vertical anchoring portions, said strips being provided at intervals with depending anchoring spurs, whereby a tie of increased structural strength with greater anchoring efficiency is produced.

The invention consists of the features of 45 construction, combination and arrangement of parts, hereinafter fully described and claimed, reference being had to the accompanying drawing, in which:

50 Figures 1, 2 and 3 are inverted perspective views of the effects of the first, second, and third steps, respectively, of the process of manufacturing the cross-tie, Fig. 3 also showing the supplementary bracing and anchoring strips applied.

Fig. 4 is a perspective top view of the completed cross-tie.

Fig. 5 is a vertical transverse section through the completed tie.

Fig. 6 is a fragmentary perspective view 60 showing a modified form of bracing and anchoring strip.

In manufacturing my improved cross-tie, as set forth in my aforesaid Patent No. 685,213, I form a blank (shown in Fig. 1 of the drawings) by cutting a section of the requisite length transversely from a bar of rolled steel or iron of T-shape in cross section, which bar may be of a length to form a plurality of said blanks therefrom. This blank is of a length exceeding that of the bed plate *d* of the cross-tie to be formed, the excess being nearly or quite equal to twice the depth of the vertical web *a*. By means of fillings *b*-*b*, formed in the upper 70 corners of the sides of the web, said web and bed plate are braced to maintain them transversely in their respective planes. I next remove from each end of the web about one-half of the aforesaid excessive length, which removal is readily accomplished by subjecting the end portions of the web to the shearing or punching action of suitable dies in a press. The lines of cutting across the web are at right angles to the bed plate 75 *d* to form vertical end walls on the web, the blank then presenting the appearance shown in Fig. 2 of the drawing. I next bend or depress the projecting ends *d*'-*d*' of the 80 horizontal portion *d* of the blank down onto the vertical end faces of the web *a*, as shown in Fig. 3 of the drawing. Said depressed portions *d*'-*d*' thus form on the ends of the tie vertical abutments or anchoring members which are braced against inward pressure, and by their hold on the road bed they 85 effectually prevent the cross-tie from being shifted endwise or laterally in relation to the track, and consequently maintain the 90 track in line.

The top portion *d* constitutes the bed plate of the tie, which bed plate is maintained in a uniform horizontal plane across the entire width thereof to provide the cross-tie with a bearing of maximum width and efficiency upon the road bed and at the same time permit free escape of water from under the 105 sides of the cross-tie, and thus obviate the liability of entrapping water under the 110

cross-tie, such entrapped water tending to loosen the hold of the tie on the road bed. Such entrapping of the water under the tie is also guarded against by limiting the depth 5 of the end walls or abutments $d' d'$, so as to prevent their projecting beneath the bottom of the web a . Furthermore, it will be observed that the horizontal bed plate d , with the continuous single web a in the center thereof, affords the most convenient access 10 for thoroughly tamping the ballast under the tie from opposite sides thereof and uniformly through the length of the tie.

In order to more effectually reinforce and 15 brace the plate d and end walls $d' d'$, as well as to secure a more reliable and efficient hold upon the ballast, I provide reinforcing or bracing strips e , one of said strips being arranged along the underside of the plate 20 d parallel with and adjacent to each of the longitudinal side edges thereof. Each strip e , which may be of iron or steel, is secured to the plate d by bolts or rivets e' at equidistant points throughout the length thereof, 25 whereby the longitudinal portions of the plate d are materially strengthened and reinforced and additional braces are provided to bear against the extremities of the walls $d' d'$ to prevent bending or deflection thereof. 30 The strips e are each provided at spaced intervals with a row or series of depending spurs or anchoring projections f , extending downwardly into the plane of the lower edges of the web a and end walls $d' d'$. 35 These spurs or anchoring projections are preferably V-shaped and extend transversely of and are cast integral with the strips e , but, if desired, as shown in Fig. 6, I may provide reinforcing strips e^2 having conical 40 anchoring spurs f^2 integral therewith or riveted thereto, which construction may be used under some conditions of service.

It will be evident that by the provision of the strips e the tie plate d will be materially

strengthened and reinforced between its side 45 edges and the vertical web a . It will also be evident that these strips will reinforce and strengthen the end walls $d' d'$. It will furthermore be evident that by the provision of the depending spurs upon the strips a more 50 efficient and reliable holding action of the tie upon the ballast will be secured, and that, as these spurs are spaced a distance apart, the free tamping of the ballast beneath the tie will be permitted, as well as the drainage 55 off of all water. The plate d is provided with the square or other angular openings g for the passage of bolts having similarly shaped heads and which fasten the rails to the tie. 60

Having thus fully described my invention, I claim:

1. A railway cross-tie comprising a tie plate of oblong rectangular form, having a vertical web extending centrally and longitudinally upon the underside thereof, said plate also having down-bent end walls abutting against the ends of said web, and reinforcing strips extending along the underside of the tie plate between the web and longitudinal edges of the tie plate and provided with depending anchoring spurs. 65

2. A railway cross-tie comprising an oblong rectangular tie plate, said plate having a vertical web extending centrally and longitudinally upon the underside thereof, and having downturned end portions resting against the ends of said web, reinforcing strips extending along the underside of the tie plate adjacent to the longitudinal edge 70 thereof and bearing terminally against the said downturned end portions of the tie plate, and spaced rows of V-shaped anchoring spurs projecting downwardly from the reinforcing strips and extending transversely thereof. 75

In testimony whereof I affix my signature.

ORVILLE MARSHALL KNOX.
